UNITED STATES PATENT OFFICE.

WINFIELD HANCOCK YOST, OF MONTREAL, QUEBEC, CANADA, ASSIGNOR TO RODGER
BALLAST CAR COMPANY, OF CHICAGO, ILLINOIS, A CORPORATION OF MAINE.

BALLAST-CAR.

1,116,864.

Specification of Letters Patent. Patented Nov. 10, 1914.

Application filed December 2, 1912. Serial No. 734,646.

To all whom it may concern:

Be it known that I, WINFIELD HANCOCK YOST, a citizen of the United States, residing at Montreal, Province of Quebec, Dominion of Canada, have invented certain new and useful Improvements in Ballast-Cars; and I hereby do declare that the following is a full, clear, and exact description thereof.

This invention relates particularly to ballast cars of the type adapted to have their loads discharged by the passing of a plow therethrough, the invention having for an object to provide, in a car of this type, an improved means whereby the bottom of the car may be arranged to facilitate discharge of the load by the plow to either or both sides as desired; the object of the invention being more specifically to make the side portions of the car floor capable of being adjusted when desired to a position sloping downwardly and outwardly. For further comprehension however of the invention and of the objects and advantages thereof reference will be had to the following description and appended claims, and to the accompanying drawings forming part of this specification in which similar reference characters indicate the same parts and wherein:

Figure 1 is a plan view of a ballast car having the invention embodied therein. Fig. 2 is an enlarged view partly in section, of a portion of the car side, with the swinging doors removed; Fig. 2^a is an enlarged detail vertical section on line 2—2 Fig. 3. Fig. 3 is a transverse section on the line 3—3 Fig. 1. Fig. 4 is a detail plan view of a portion of the car illustrating particularly the mounting of the movable marginal floor portions. Fig. 5 is a detail perspective view of the device for supporting the free sides of the adjustable floor sections.

In the drawings I have illustrated my invention embodied in a car having an understructure comprising a center sill 2 and transverse arms 3, the outer ends of the arms 3 having the side stakes 4, which support the swinging side walls 5 in a well known manner, mounted thereon, these parts being of any well known or approved construction.

The floor of the car comprises an intermediate horizontal portion 6 which may be nailed to longitudinal and transverse filler strips or nailing pieces, 7 and 8 respectively, which are placed upon the center sill 2 and transverse arms 3, the side edges of such

floor being supported by longitudinal beams 9 which are bolted at each end to brackets 9' riveted to the arms 3. This floor 6 does not extend the full distance between the side walls of the car, the present invention relating to the means for closing the space between the said floor and side walls to facilitate the discharging of the load by the plow to either or both sides of the car. This means comprises a plurality of adjustable marginal sections arranged in two series, 10 and 11 respectively, one series on each side of the car, each section extending from one transverse member 3 to the next one. These sections are hinged at their inner sides to the car frame in a suitable manner, the sections being here shown as made up of a plurality of boards extending longitudinally of the car and bolted at their ends as at 12 to angle iron facing strips 13 one flange of which extends under the ends of the boards and the other across the edges thereof. These angle irons extend inwardly beyond the adjustable floor sections and have their vertical flanges longitudinally slotted as at 14, through which slots pass U-bolts 15 secured to the beams 9 and by means of which the angle irons are hinged to the frame. To accommodate these angle irons the edges of the floor 6 are transversely slotted as at 16 while the beams 9 are formed with beveled notches 17 to allow the angle irons to swing downwardly. These side floor sections are adapted to be adjusted either to a position on a level with the fixed door 6 and extending from the sides thereof to the swinging side wall members 5 as shown at the right side of Fig. 3, or to a position inclining downwardly and outwardly as shown at the left side of Fig. 3, in which latter position they form discharging aprons to facilitate the discharging of the load by the plow and obviate the liability of rocks or the like becoming jammed between the plow and side stakes and breaking the latter, the plow being indicated at X and resting at its sides upon the outer ends of the transverse filler strips 8, the transverse members (comprising arms 3 and strips 8) being spaced sufficiently closely together to form a runway for the side runners of the plow when the movable sections are in inclined position. When in inclined position these sections are supported at their ends upon cleats 18 secured to filler blocks 19 bolted as at 19¹ to the trans-

verse arms 3, these filler blocks being employed to prevent leakage of material between the ends of the floor sections and the arms 3 when the former are in inclined position. These movable sections when in inclined position constitute the upper portions of the discharging aprons, the lower portions of such aprons being fixed as shown at 20 and mounted upon longitudinal joists 21, 10 22 supported by the side sills 23 of the car which are here shown of Z-form in cross section and which extend under and are secured to the transverse arms 3 at the outer ends thereof. The lower edges of the swinging 15 side wall sections abut against these fixed members 20 when in closed position, being locked by any well known means indicated at 24.

The adjustable floor sections are supported in their raised positions by suitable releasable means, that which I have devised for the purpose and here illustrated comprising for each section a pair of short rigid lock bars 25 located one at each end of the 20 section and pivoted at one end in brackets 26 bolted to the underside of the angle irons 13 at the outer ends thereof and which are adapted to be swung upwardly over, and rest upon, the transverse arms 3 adjacent the 25 ends thereof and thus support the free edges of the floor sections, the ends of the filler strips 8 being cut off just short of the inner faces of the side stakes to accommodate the lock bars. The inner edges of the floor sections are supported by the inner ends of the 30 angle irons which rest, as indicated at the point 30, upon the joists 9.

In using a car embodying my invention the movable side floor members will be lowered on both sides of the car when the load 40 is to be plowed off to each side. When the load is to be plowed off to one side only the floor members on the opposite side will be raised. To raise and lock these members it is only necessary to swing them up a slight 45 distance above the fixed floor and then swing the lock bars 25 over the arms 3 and allow

the members to drop into place. To lower the floor members they are first raised sufficiently to allow the lock bars to drop off the 50 arms 3.

What I claim is as follows:

1. In a car of the class specified, having a fixed horizontal flooring and swinging side wall members spaced outwardly therefrom, 55 adjustable side floor portions extending from the said intermediate floor to the said side wall members, for the purpose set forth.

2. In a car of the class specified, having a fixed horizontal flooring and swinging side 60 wall members spaced outwardly therefrom, adjustable side floor portions extending from the said intermediate floor to the said side wall members, such side floor sections being adapted to be adjusted from a position 65 on a level with the fixed floor to a position inclining downwardly and outwardly, for the purpose set forth.

3. A car of the class specified having an intermediate horizontal flooring fixed with 70 relation to the car, and downwardly and outwardly sloping side aprons, the said side aprons having adjustable upper portions, for the purpose set forth.

4. A car of the class specified having an 75 intermediate horizontal flooring fixed with relation to the car, and downwardly and outwardly sloping side aprons, the said side aprons comprising fixed lower portions and adjustable upper portions.

5. A car of the class specified having a 80 floor comprising an intermediate portion and adjustable side portions, the said side portions comprising boards the ends of which are set in the angle of angle bars, the 85 said angle bars extending inwardly and being hinged to the car.

In testimony whereof, I have signed my name to this specification, in the presence of two subscribing witnesses.

WINFIELD HANCOCK YOST.
